UNITED STATES PATENT OFFICE

LOYAL GRANT ROBBERTS, OF SANTA MONICA, CALIFORNIA

ADVERTISING APPARATUS

Application filed May 9, 1929. Serial No. 361,712.

This invention relates to advertising apparatus and more especially to apparatus of the type including an endless traveling curtain of panels bearing advertisements.

5 An object of this invention is to provide a novel and effective display curtain and drive means therefor whereby to facilitate the change of length of the curtain and to permit ready change of panels from time 10 to time.

An additional object is to provide an illuminating means which has the dual function of illuminating the front, exposed area of the curtain and also, by forming a mirror 15 for observers, to draw attention to the apparatus.

Additional objects, advantages and features of construction and details and operation will be made manifest in the ensuing 20 description of the herewith illustrative embodiment; it being understood that modifications, variations and adaptations may be resorted to within the scope, principle and spirit of the invention as it is hereinafter 25 claimed.

Figure 1 is a front elevation of the apparatus.

Figure 2 is vertical section of the cabinet; interior parts being disclosed.

30 Figure 3 is a horizontal cross-section.

Figure 4 is a detail of sectional curtain structure.

The apparatus includes a suitable housing or cabinet 2 presenting an open front for 35 display of the effective advertising device which passes in plane presentation to the eye.

At each side of the cabinet is an angularly arranged mirror 3 serving not only to reflect 40 images of passersby but also reflecting light from shells 4 which extend along the outer edges of the mirrors and partly conceal lighting means 5.

An additional attractive feature is a clock 45 6 arranged on top of the cabinet.

The display media consists of an endless curtain 10 which preferably is built up of individual advertising sections or panels 10' which are joined edge to edge by any desired form of fasteners 11.

This endless curtain is guided over a number of top rollers 12 and bight rollers 13 according to the capacity of the cabinet and length of the curtain.

One of the rollers, as 13 is a free-floating 55 means to keep the curtain under desired tension.

Means are provided to effect the desired feed or advance of the curtain so that its whole display area will appear in a cycle at 60 the front of the case. The feed means includes an endless belt 15 running around a front foot roller 16 and thence up to the front top roller 12 then down to a floating tensioning roller 17 operative either by its 65 own weight or other means, as a spring 18 to draw the belt taut onto a driving drum 19 about which a bight of the belt passes.

The drum is driven by any desired form of transmission 20 from motor 21. 70

The advertising curtain 10 and the belt 15 run, the former on the latter, up or down from the front rollers 12—16 smooth and flat at the front window of the cabinet and the curtain bends down over the back of the 75 front roller 12 and runs off the rear bight of the belt at the back of drum 19 so that there is ample area of contact between the drive belt and the curtain to insure the progressive shift of the curtain to secure display 80 of the advertisements thereon.

It will be seen that it is not necessary to alter the position or the length of the drive belt when any changes are made in the display curtain. 85

What is claimed is:

1. In an advertising apparatus, an endless display curtain, upper and lower, guide rollers between which the curtain operates in a front plane position, and drive means 90 including an endless driven belt running over the guide rollers and one which the plane front of the curtain is lapped.

2. In an advertising apparatus, an endless display curtain, a system of top and bottom guide rollers and other bight rollers for the curtain, and an endless, driven belt running directly on the said front rollers and thereon being overlapped by bends 95 of the curtain for cooperative driving relation 100.

tion and a power roller back from the guide rollers and on which the belt is looped.

3. In an advertising apparatus, an endless display curtain, a system of top and bottom 5 guide rollers and other bight rollers for the curtain, an endless, driven belt running directly on the said front rollers and thereon being overlapped by bends of the curtain for cooperative driving relation, and independent means for tensioning the belt and 10 the curtain and whereby the latter is drawn snug to the former at all times.

4. In an advertising apparatus, an endless display curtain, a system of top and bottom 15 guide rollers and other bight rollers for the curtain, an endless, driven belt directly on the said front rollers and thereon being overlapped by bight bends of the curtain for effective cooperative driving relation, independent means for tensioning the belt and 20 the curtain, and a drive drum about which the belt has a bight from one of the guide rollers; said curtain lapping on the drive drum bight of the belt.

25 5. In an advertising apparatus, a belt device, spaced front rollers, a tensioning roller and a driving roller, said belt having a bight about the front rollers and the tensioning roller and a bight to the drive roller, and a 30 display curtain lapping the front bight and the drive bight of the belt, and bight rollers for the curtain.

35 6. In an advertising apparatus, a belt device, spaced front rollers, a tensioning roller and a driving roller, said belt having a bight about the front rollers and a bight about the tensioning roller and a bight to the drive roller, and a display curtain lapping the front bight and the drive bight of the belt, 40 length-forming bight rollers for the curtain, and bight means to tension the curtain on its driving belt.
